UNITED STATES PATENT OFFICE.

ROBERT DE COURSEULLES, OF PARIS, FRANCE, ASSIGNOR TO SOCIÉTÉ SCHNEIDER & CO., AND COMPAGNIE DES FORGES & ACIERIES DE LA MARINE & D'HOMECOURT, BOTH OF PARIS, FRANCE.

DEVICE FOR THE HORIZONTAL AIMING OF TURRETS COMPRISING SEVERAL GUNS.

Application filed August 1, 1927, Serial No. 209,892, and in France August 6, 1926.

It is well known that in ship turrets comprising several guns, the firing of a lateral gun will cause a disaiming motion of the turret about its axis of revolution.

5 Should it be desired to avoid this disaiming motion, generally known under the name of "turning" it would be necessary to provide for considerable strains upon the parts controlling the horizontal aiming and consequently to give them sizes which are exaggerated relatively to the stresses which are 10 to be transmitted during the aiming operation.

One has thus been induced to arrange upon 15 the driving means of the aiming pinion, apparatuses allowing the "turning" while limiting the same to an acceptable value.

The known apparatuses used for attaining this result comprise:

20 1—Either a stress limiting device which is generally a friction one.

2—Or an elastic spring sleeve.

In the first case, after the disaiming, produced by the firing, the pointer must return 25 to the turret to the direction of the aim.

In the second case, this return is effected automatically but in a sudden manner and after a certain number of oscillations. The stress exerted upon the pinion is greater than 30 in the first case, as the springs have to store a work similar to the one which is absorbed by the friction of the first case and this work is for the most part restored to the turret.

The present invention relates to a device 35 possessing the advantages of the one and the other systems, that is to say the automatic return of the turret to the firing position without any oscillation with a minimum stress or strain upon the teeth of the driving pinion.

40 Moreover, the same allows to introduce into the aiming or pointing movement, a correction (derivation or the like).

It consists in the addition to the shaft of 45 the pinion controlling the lateral aiming of the turret of a differential gear whose ring of planetary wheels carries external teeth meshing with a rack maintained in its middle position by one or more springs and whose longitudinal motion is braked by an hydraulic brake.

At firing, the revolution of the turret determines the displacement of the rack and consequently the compression of the spring.

The vis viva in excess is absorbed by the 55 hydraulic brake.

The rack can be replaced by a worm which can act as a rack.

In this case, the revolution of this screw, controlled by hand or by a special motor 60 allows the introduction of the correction to be made in the aiming.

The annexed drawing shows, by way of example, two embodiments of the object of the 65 invention.

Figs. 1 to 3 relate to a first device provided with a rack.

Figs. 4 to 6 relate to a second device provided with a worm.

Fig. 1 is a vertical section through the 70 axis of the pinion controlling the aiming in the lateral direction.

Figs. 2 and 3 are horizontal sections made respectively according to 2—2 and 3—3 of 75 Fig. 1.

Fig. 4 is a vertical section made through the axis of the pinion controlling the aiming in the lateral direction, Figs. 5 and 6 are horizontal sections made respectively according to 5—5 and 6—6 of Fig. 4.

In Figs. 1 to 3, the pinion 1 controlling the lateral aiming and meshing with the fixed toothed ring 2 is carried by the driving shaft 3 divided into two parts by the differential gear 4.

The upper part 3^a carries a worm wheel 5 operated by a worm 6 moved by a motor 7.

The external ring 8 of the differential gear 4 carries a toothed ring 9 gearing with a 90 rack 10.

This rack 10 can be shifted to the extent allowed by the frame 11. It is maintained in the middle position by a spring 12 under initial tension, washers 13 acting as a bearing for the spring being arranged so that 95 the same will be compressed whatever the direction of motion of the rack 10 may be.

On the other hand, a piston 14 connected to the rack 10 moves within a cylinder 15 filled with liquid, similar to the brakes for the recoil of guns.

A tank 16 communicating through a small orifice with the cylinder 15 insures the filling of this cylinder and allows the expansion of the liquid contained therein.

105 In Figs. 4 to 6, the arrangement is the same except that the rack is replaced by a worm 10^a capable of being displaced in the

direction of the axis and provided with a system of springs 12^a and with a brake 15^a similar to the previous one.

The rotation of the worm 10^a is effected by means of a toothed wheel 20 connected with the worm 10^a by means of a sliding key. This wheel 20 itself is operated by a suitable motor 17 through the medium of a pinion 18 and of a chain 19.

10 During the firing of a gun placed outside the axis of the turret, the same has imparted thereto an impulse tending to cause the shaft 3 of the pinion 1 to revolve. The upper part 3^a of the shaft 3 being immobilized by the worm wheel 5 under the action of the differential gear, the ring 8 will revolve about its axis at an angular speed which is half that of the pinion. The rack 10 or the worm 10^a then operating as a rack moves in compressing 20 the spring 12 and in causing the liquid of the cylinder 15 to pass from one face of the piston 14 to the other. The tension of the spring 12 is only sufficient to return the turret to the firing position. The work in excess of the one required for compressing the spring is absorbed by the brake 14-15.

The brake which is represented is of the kind comprising grooves and orifices of section varying in accordance to the position 30 of the piston; it could be of any other system, with loaded valves for example.

In the second device, (Figs. 4 to 6) the corrections, deviations or the like, to be brought to aiming are introduced in causing the rotation of the screw 10^a acting in this case as a worm by means of a motor 17 through the medium of the wheels 20 and 18 and of the chain 19.

Having thus described my apparatus, what 40 I claim as new therein, and my own invention, is:—

1. Device for the horizontal aiming of turrets with several guns comprising a differential gear arranged upon the means for controlling this aiming, a ring of planetary wheels in this differential gear, a rack meshing with teeth carried by this ring, means for braking the longitudinal displacement of this

rack, and means for automatically returning the said rack to the firing position. 50

2. Device for the horizontal aiming of turrets with several guns, comprising a differential gear arranged upon the means for controlling this aiming, a ring of planetary wheels in this differential gear, a worm meshing with teeth carried by this ring, means for braking the longitudinal displacement of this worm, springs for automatically returning the same to the firing position and means for causing this worm to rotate about its axis at 60 will.

3. Device for the horizontal aiming of turrets with several guns, comprising teeth in connection with the turret, a driving pinion meshing with these teeth, a shaft connected 65 with this pinion, a first planetary differential gear at the other end of this shaft, a second planetary gear fast upon a shaft operated from a motor, planetary pinions between the planetary gears, a ring carrying 70 the axes of these planetary pinions, teeth upon this ring, a rack meshing with these teeth, springs for returning automatically this rack to its middle position, a piston connected with the rack and a cylinder filled 75 with liquid in which this piston moves.

4. Device for the horizontal aiming of turrets with several guns comprising teeth in connection with the turret, a driving pinion meshing with these teeth, a shaft connected 80 with this pinion, a first planetary differential gear at the other end of this shaft, a second planetary gear fast upon a shaft operated from a motor, planetary pinions between the planetary gears, a ring carrying the axes of 85 these planetary pinions, teeth upon this ring, a worm meshing with these teeth, springs for automatically returning this worm to its middle position, a piston connected with the worm and a cylinder filled with liquid in 90 which this piston moves, and means for causing this worm to rotate about its axis at will.

In testimony whereof I have hereunto affixed my signature.

ROBERT DE COURSEULLES.
